MEANS AND METHOD FOR CONTROLLING OR PREVENTING OSCILLATIONS IN VACUUM TUBE CIRCUITS

Application filed October 18, 1924. Serial No. 743,269.

My invention relates to vacuum tube circuits; and the same has for its object more particularly to provide a simple, efficient and reliable amplifying system in which the effects of undesirable feed back action are neutralized or prevented.

Employed in my invention. Some inductive reactance, as desirable, may be included in such impedance, provided that the ohmic value of the resulting impedance, as hereinafter described, is such as to produce the required potential drop at the different frequencies.

Further, said invention has for its object to provide a system of the character specified in which undesirable potentials, or the effects thereof, such as those due to the inter-electrode capacity of the tube, are neutralized, or prevented, without the dissipation of appreciable energy, and the reduction of amplifying power.

In the accompanying drawings a number of circuits are shown illustrating a variety of embodiments of the invention.

Further, said invention has for its object to provide a system of the character specified which, without adjustment, is effective over its entire frequency range in neutralizing or opposing said undesirable feed back potentials.

In the drawings:

Further, said invention has for its object to provide a system of the character specified in which resistance is employed to control the value of the neutralizing potential so that the latter effects neutralization of the undesirable feed back potential.

Fig. 1 is a radio receiving circuit comprising one stage of tuned radio frequency amplification and a crystal detector.

Further, said invention has for its object to provide a system of the character specified in which current from certain of the circuits thereof is caused to traverse a portion of another circuit, and in which the resulting potential drop developed in said portion, as a result of the resistance thereof, is such as to effect the neutralization of the undesirable feed back potentials.

Fig. 2 is a radio receiving circuit comprising two stages of radio frequency amplification, a detector and one stage of audio frequency amplification.

Further, said invention has for its object to provide a novel method for neutralizing or opposing undesirable feed back potentials. Other objects will in part be obvious and in part be pointed out hereinafter.

Fig. 3 is an alternative arrangement with respect to that of Fig. 2.

To the attainment of the aforesaid objects and ends, my invention consists in the several steps comprising the method, and in the novel features of construction, and in the combination, connection and arrangement of parts hereinafter more fully described and then pointed out in the claims.

Fig. 4 is a radio receiving circuit comprising one stage of radio frequency amplification and a vacuum tube detector.

For developing the required neutralizing potential, or potential drop, an impedance consisting primarily of resistance is em-

Fig. 5 is a reflex receiving circuit comprising two stages of radio frequency amplification, a crystal detector and three stages of audio frequency amplification—two of the latter being reflexed.

In the circuit of Fig. 1 vacuum tube 1 is a radio frequency amplifier having an input circuit comprising coil 2 and variable condenser 3 and an output circuit comprising coil 4 and plate battery 5. The input circuit is shown associated with an antenna system 6. A filament battery 7 is provided for heating the filament of the vacuum tube and a rheostat 8 is inserted in series with the battery 7 for adjusting the temperature of the filament. The output circuit of the amplifier tube may be tuned by the variable condenser 10, the coil 9 forming a part of the circuit in which is included the crystal detector 11 and telephone 12.

Amplifying circuits, such as the simple circuit at Fig. 1 serving as one example, because of the inter-electrode capacity of the tube, and other coupling, and, particularly, when the input and output circuits are tuned to the same frequency feed back energy from one circuit to another.

The potentials thus fed back are often un-

60

100

desirable, particularly in radio frequency amplifying circuits, as the same tend to cause undesirable oscillation of the tube or tubes of the system.

5 I obviate or neutralize these undesirable feed back potentials by means of opposing or neutralizing potentials. For this purpose a neutralizing resistance 13 is disposed in a circuit portion common to both the input and 10 output circuits in series with the input electrodes of the tube 1. Since the tube 1 is unidirectional, the current flows therethrough from the plate to the filament thereof, and thereby develops a potential drop between 15 the terminals of said resistance 13 which is such that a negative potential with respect to the filament is impressed upon the grid. Any increase of plate current increases this negative potential and likewise any decrease 20 of plate current decreases the negative potential on the grid. When the resistance 13 has the required value the potential developed therein neutralizes or opposes the undesirable feed back potential.

25 The value of neutralizing resistance required to effect complete neutralization depends upon the magnitude of feedback action to be overcome. In a circuit such as that shown in Fig. 1, the required resistance 30 usually ranges between 5 and 30 ohms and may be considerably higher if the absorption of energy from the amplifier circuit is extremely low. In circuits similar to that of Fig. 1 which have actually been constructed, 35 the value of resistance required has been found to range from about 7 to 15 ohms. It is evident that the resistance loss in the neutralizing resistance is insignificant when the ratio of this resistance to the total resistance 40 of the output circuit is considered.

The resistance 13, when once adjusted to the correct or balancing value, according to the amount of feed back action in the circuit in which the same is employed, serves, without further adjustment thereof, to neutralize 45 the undesirable feed back potentials throughout the wave-length range of the system. Under such conditions the grid potential variations due to undesirable feed back action will 50 be cancelled by the changes in voltage drop across resistance 13. Should the value of the resistance employed be increased or decreased from the critical or proper value, it has been found that oscillation of the tube occurs. 55 For instance, in actual tests, it has been found that a resistance of the value of hundreds of ohms disposed in the position of the resistance 13 (Fig. 1) causes oscillation of the tube, and that the strength of such oscillation increases as the value of the resistance is increased up to several thousand ohms.

60 When the resistance employed exceeds the value necessary for a balance, the entire system is unstable, the grid potential becoming too much positive as the same becomes more

positive and too much negative as the same becomes more negative, the excess of neutralizing potential tending to cause oscillation.

In like manner, if the value of the resistance is decreased below the critical or balancing value oscillation of the tube also occurs, because there is then an excess of undesirable feed back potential.

70 It is therefore apparent that the resistance 13 does not prevent the oscillation of the tube because of the damping action thereof, but on the contrary serves to control the neutralizing potential so that the undesirable feed back potential is neutralized.

75 In the circuit of Fig. 2 vacuum tubes 14 and 15 are radio frequency amplifiers; tube 16 is a detector and tube 17 is an audio frequency amplifier. In this circuit two neutralizing resistances, 18 and 19, are provided for neutralizing or controlling undesirable feed back 80 potentials in the two radio frequency stages. Resistance 18 is included in the plate filament circuit of tube 14, in the same manner as resistance 13 in Fig. 1. Resistance 19 is likewise included in the plate filament circuit or 85 output circuit of tube 15. These neutralizing resistances are operable, independently, to produce the required varying potential drop to be impressed upon the grids of their respectively associated tubes. Coils 20 and 21 90 having sufficient inductance substantially to prevent the passage of radio frequency current, are inserted in the filament battery leads interconnecting the filaments of the two radio frequency tubes. By virtue of these coils the high frequency current in the output circuit of tube 14 is precluded from flowing through neutralizing resistance 19 and likewise the high frequency current in the output circuit of tube 15 is precluded from flowing through 95 neutralizing resistance 18. The neutralization of each tube is therefore maintained independent of the other. The inclusion of coils 20 and 21 is not strictly essential because the circuit can be adjusted to operate satisfactorily without them, but their use is desirable in the circuit shown in order to prevent upsetting of the neutralization in one or both radio frequency tubes, upon interchanging of 100 unlike tubes. Further, more exact neutralization can be readily obtained when the coils 105 20 and 21 are provided.

110 With the circuit of Fig. 2 it has been found necessary to provide two independent filament heating batteries, 22 and 23, in order to preclude feeding back of audio frequency current from the detector and audio stages through the neutralizing resistances and thence into the input circuits of the radio frequency amplifiers. This sort of feedback action causes undesirable modulation of the radio frequency current, and must of necessity be prevented or kept within such limits that its effect is not detrimental.

115 The circuit of Fig. 3 is like that of Fig. 130

2 in that it comprises two stages of radio frequency amplification, a detector, and one stage of audio frequency amplification. In this circuit the vacuum tubes 5 are designated 14', 15', 16' and 17' and these correspond with vacuum tubes 14, 15, 16 and 17 of Fig. 2. In the arrangement of Fig. 3 the necessity for providing two independent filament batteries has been obviated. In this case the plate battery 24 is connected to the plates of the radio frequency amplifier tubes, through high inductance paths including radio frequency choke coils 10 25 and 26 respectively, each of which is designed to offer high impedance to both radio frequencies and audio frequencies. Condensers 29 and 30 are provided to block the flow 15 of direct current through the primary windings of the radio frequency transformers, 31 and 32. Each condenser should be of sufficient size to permit the flow of radio frequency current of the order of frequency to be dealt with. Neutralizing resistances 18' and 19' are included in the output circuits of 20 25 their respectively associated vacuum tubes 14' and 15'. It will be noted that only radio frequency currents can flow through the neutralizing resistances in this instance and that there is no path whereby audio frequency 30 currents from the detector or audio frequency stages can find their way to the neutralizing resistances and hence that there is no possibility of modulation occurring due to audio-frequency feedback. As between Figs. 2 and 35 3 the latter is of course the preferred embodiment because of the absence of necessity for providing two independent filament batteries. The elements shown in Figs. 2 and 3 and not specifically described are regarded as 40 being so well known in the art that no explanation of their function is necessary in order to convey a clear understanding of the invention and its operation.

The magnitude of neutralizing resistance, 45 which it has been found necessary to employ in the circuits of Figs. 2 and 3 usually ranges between 7 and 15 ohms for each element.

A further advantage inherent in the arrangement of Fig. 3, as compared with those 50 of Figs. 1 and 2 arises from the fact that the battery current does not flow through the neutralizing resistances which therefore do not impress any normal bias on their respective grids. If a grid bias is desired in the 55 circuit of Fig. 3 it may be provided in the usual manner, that is by the addition of a grid battery.

The diagram of Fig. 4 represents a receiving circuit comprising one stage of radio 60 frequency amplification and a vacuum tube detector. The embodiment of the invention disclosed in this circuit is somewhat of a departure from those disclosed in the previous figures in that the radio frequency energy 65 utilized for developing the neutralizing po-

tential drop instead of being taken directly from the plate circuit of the radio frequency amplifier is taken from the input circuit of the next succeeding tube, which in this instance happens to be a detector tube. Tracing 70 the circuit of the neutralizing resistance 33 it will be seen to include the secondary winding of the radio frequency transformer 34, grid condenser 35 in parallel with the grid leak resistance 36 and the grid and filament 75 of detector tube 37. The flow of radio frequency current in this circuit depends upon the grid filament capacity in the detector tube. The windings of the transformer 34 are shifted as indicated so that the flow of 80 radio frequency current in the circuit of the neutralizing resistance is in the proper direction. It is found that this circuit arrangement works equally as well as any of those previously described and it has the inherent 85 advantages that there is no normal grid bias due to the battery current and no choke coils are required. The same or a similar arrangement to that shown in Fig. 4 may be utilized in circuits employing a larger number of 90 vacuum tubes. It is thought that the adaptability of this idea to other circuits is readily apparent.

The diagram of Fig. 5 illustrates an adaptation of the present invention to a circuit 95 of the reflex type. This circuit includes two reflexed tubes 38 and 39, a crystal detector 40, and a non-reflexed audio frequency amplifier 41. In this system 42, 43 and 44 are 100 radio frequency transformers. The received signals are amplified successively by the radio frequency amplifiers and finally passed through transformer 44 to the circuit of crystal detector 40, wherein they are rectified and then passed through the first audio 105 frequency transformer 45 to the input circuit of vacuum tube 38, which functions as both the first radio and first audio amplifier. The amplified audio frequency signals are 110 passed from the output circuit of tube 38 through audio frequency transformer 46 to the input circuit of amplifier tube 39, where they are again amplified and then passed through audio frequency transformer 47 to the input circuit of the audio amplifier 41 115 in which the signals are still further amplified. A jack 48 is shown in the output circuit of tube 41 for the usual loud speaker connection.

To the extent thus far described, the circuit of Fig. 5 is of the ordinary reflex type. A neutralizing resistance element 49 is shown inserted in a circuit including the plate and filament electrodes of the tube 39, 120 the primary winding of transformer 44 and 125 a condenser 50. It will be noted that the fixed terminal of neutralizing resistance 49 is connected directly to filament and that the adjustable terminal is connected to the grid of tube 38, through the secondary wind- 130

ing of transformer 45. The radio frequency current flowing in the output circuit of tube 39 must pass through neutralizing resistance 49, and in doing so sets up a variable potential difference which is impressed between the grid and filament of tube 38. The ohmic value of neutralizing resistance 49, connected in circuit, is adjusted to the proper point to effect neutralization. It is found that the single neutralizing resistance 49, receiving its energy from the output circuit of tube 39 and impressing its derived potential difference across the grid and filament electrodes of tube 38, is effective to neutralize the feedback action in both radio frequency amplifiers. It is presumed that the neutralizing potential impressed upon the grid of tube 38 is impressed in amplified form upon the grid of tube 39. Whether or not this is a correct explanation is uncertain and whether or not exact neutralization of both radio frequency amplifier tube is effected is likewise uncertain. It is, however, entirely certain that the generation of oscillations in both radio frequency amplifier tubes can be effectively prevented by the use of the single neutralizing resistance as shown. Likewise regeneration can be completely eliminated in both radio frequency stages. Whether or not this involves a slight over-neutralization of one or the other radio frequency amplifiers has not been determined, but at any rate the degree of amplification is not perceptibly diminished over that obtainable in the radio frequency stages of the circuits previously described utilizing separate neutralizing resistances for each radio frequency stage.

In the circuit of Fig. 5 the primary of the transformer 47 serves as a high inductance or choke, like the elements 25 and 26 at Fig. 3, in series with the plate battery, and offering a high impedance to radio frequencies.

The resistance 49 is in a high frequency circuit arranged exteriorly of and in parallel with the portion of the plate circuit including said battery and said primary. The condenser 50 in the radio frequency circuit serves to block the flow of direct current through the resistance 49, and hence no normal bias is impressed by the battery upon the grid of the tube 38.

It is apparent that the invention herein described is capable of various modifications and that its use is not limited to the particular types of circuits herein described. Furthermore the invention is not limited to use in conjunction with radio frequency amplifiers, but is equally applicable to audio frequency amplifiers wherever there is any tendency toward excessive regeneration or audio frequency howling in such amplifiers.

I claim:

1. The herein-described method of stabilizing a vacuum tube amplifier having an in-

herent tendency towards self-oscillation due to an undesirable feed-back of energy, which consists in taking a signaling frequency current from the output side of a tube thereof, causing the same to traverse a resistance, 70 thereby developing a potential difference which fluctuates at signaling frequency, and impressing said potential difference fluctuating at signaling frequency across the input electrodes of a vacuum tube in opposition to 75 the potential difference impressed across said input electrodes due to the feed-back action.

2. The herein-described method of stabilizing a vacuum tube amplifier having an inherent tendency towards self-oscillation at 80 high frequency due to an undesirable feed-back of energy, which consists in taking a high frequency current corresponding to that in circuits at the output side of a tube, causing the same to traverse a resistance, thereby 85 developing a potential difference which fluctuates synchronously with and proportionately to said high frequency current, and impressing at least a part of said fluctuating potential difference across the input electrodes of a vacuum tube to effectively oppose 90 at every instant the corresponding high frequency potential difference impressed across the electrodes as a result of said feed-back action. 95

3. The herein-described method of stabilizing a radio frequency vacuum tube amplifier having an inherent tendency towards self oscillation at high frequencies due to an undesirable feed-back of energy, which consists in taking a high frequency current from the output circuit of one tube, causing the same to traverse a portion of the input circuit of another tube, thereby developing a potential difference which fluctuates synchronously 100 with and proportionately to said radio frequency current, and impressing said fluctuating potential difference across the input electrodes of said second named tube to effectively oppose at every instant the corresponding radio frequency potential difference impressed across said electrodes as a result of said feed-back action. 105

4. A high frequency amplifier comprising a vacuum tube having circuits at the input and output sides thereof including high frequency portions, and a resistance included in circuit with certain of the high frequency portions at the output side of said tube and traversed by the high frequency current to develop a corresponding high frequency potential difference across said resistance; said resistance being included in circuit with the input electrodes of said tube for impressing said high frequency potential difference 120 across the same in opposition to the corresponding high frequency potential difference impressed across the same as a result of undesirable feed-back action. 125

5. A high frequency amplifier comprising 130

a vacuum tube having circuits at the input and output sides thereof including high frequency portions, and a resistance included in circuit with certain of said high frequency portions at the output side of said tube and traversed by high frequency current to develop a corresponding high frequency potential difference across said resistance; said resistance being included in circuit with the input electrodes of said tube for impressing said high frequency potential difference across the same, and adjusted to effectively oppose at every instant the corresponding radio frequency potential difference impressed across said electrodes as a result of undesirable feed-back action.

6. A high frequency amplifier comprising a vacuum tube having circuits at the input and output sides thereof including radio frequency portions and having a coupling tending to cause self oscillation due to regenerative feed-back action; the input electrodes of said tube having resistance in series therewith connected in circuit with certain of said high frequency portions at the output side of said tube and traversed by high frequency current to develop a corresponding high frequency potential difference across said resistance; and said coupling and said resistance being relatively adjusted to impress across said input electrodes a high frequency potential difference having a value to effectively oppose at every instant the corresponding high frequency potential difference impressed across said electrodes as a result of said feed-back action.

7. A multi-stage high-frequency vacuum tube amplifier comprising a plurality of vacuum tubes coupled in cascade, each of said vacuum tubes having an input circuit and an output circuit, an ohmic resistance and a condenser in series, circuit connections including said ohmic resistance and condenser whereby high-frequency current derived from and corresponding to the high-frequency current in certain of said output circuits is caused to traverse said ohmic resistance and said condenser in series, whereby a corresponding high-frequency potential difference is developed across said ohmic resistance, and circuit connections for impressing said developed high-frequency potential difference across the input electrodes of certain of said vacuum tubes to effectively oppose any high-frequency potential difference which may be impressed across said input electrodes as a result of undesirable feed-back action.

8. A multi-stage high-frequency vacuum tube amplifier comprising a plurality of vacuum tubes coupled in cascade, each of said vacuum tubes having an input circuit and an output circuit, an ohmic resistance and a condenser in series, circuit connections including said ohmic resistance and condenser whereby high-frequency current derived from and

corresponding to the high-frequency current in certain of said output circuits is caused to traverse said ohmic resistance and said condenser in series whereby a corresponding high-frequency potential difference is developed across said ohmic resistance, and circuit connections for impressing said developed high-frequency potential difference across the input electrodes of certain of said vacuum tubes to effectively oppose any high-frequency potential difference which may be impressed across said input electrodes as a result of undesirable feed-back action; said condenser being effective to regulate the impedance of the circuit including said ohmic resistance proportionately to the frequency of operation, thereby automatically increasing the opposing effect as the tendency toward self-oscillation increases.

9. An amplifying system comprising a vacuum tube having radio frequency circuits at the input and output sides thereof in operative relation to said tube, a source of space current for operating the system, and a resistance common to the input circuit of said tube and a radio frequency circuit at the opposite side of said tube and traversed by high frequency currents for developing a high frequency potential difference across said resistance and impressing the same across the input electrodes of said tube in opposition to the corresponding high frequency potential difference impressed across said electrodes as a result of undesirable feed back action, said resistance being disposed exteriorly of the circuit traversed by the space current to exclude the latter therefrom.

10. An amplifying system comprising a vacuum tube having radio frequency circuits at the input and output sides thereof in operative relation to said tube, a source of space current for operating the system, and a resistance common to the input circuit of said tube and a radio frequency circuit at the opposite side of said tube and traversed by high frequency current for developing a high frequency potential difference across said resistance and impressing the same across the input electrodes of said tube in opposition to the corresponding high frequency potential difference impressed across said electrodes as a result of undesirable feed back action, said resistance being disposed exteriorly of the circuit traversed by the space current to exclude the latter therefrom, and means serving to exclude radio frequency current from the circuit traversed by space current.

11. An amplifying system comprising a vacuum tube having radio frequency circuits at the input and output sides thereof, a source of space current therefor, a resistance in the input circuit of said tube and in a high frequency circuit at the opposite side of said tube in shunt with said source of space current, said resistance developing a high

frequency potential difference and impressing the same across the input electrodes of said tube in opposition to the corresponding high frequency potential difference impressed across said electrodes as a result of undesirable feed-back action, an inductance for excluding radio frequency current from the circuit of said source of space current, and a capacity for excluding the space current from said resistance.

12. An amplifying system comprising a plurality of vacuum tubes, input and output circuits for said tubes including radio frequency portions, and impedance means associated with the input circuit of one tube and with the radio frequency portion of the output circuit of another tube, and serving to impress a radio frequency potential drop between the input electrodes of certain of said tubes in opposition to the corresponding potential drop impressed therebetween as a result of undesirable feed back action.

13. An amplifying system comprising a plurality of vacuum tubes associated in tandem, input and output circuits for said tubes having radio frequency portions, and a neutralizing resistance included in the input circuit of one of said tubes and in the radio frequency portions of the output circuit of another of said tubes; the arrangement being such that currents in said last mentioned output circuit are caused to traverse said neutralizing resistance, and that the radio frequency potential drop thereby developed is impressed across the input electrodes of at least one of said tubes to oppose the corresponding potential drop resulting from undesirable feed-back action.

14. An amplifying system comprising a plurality of vacuum tubes associated in tandem, input and output circuits for said tubes, a neutralizing resistance element in the input circuit of one of said tubes and in the output circuit of another of said tubes, a source of space current arranged exteriorly of the portion of said output circuit including said resistance element, an inductance in series with said source of space current exteriorly of the portion of said output circuit including said resistance element, and a capacity in said last named portion of said output circuit; said resistance element serving to impress a potential drop between the input electrodes of certain of said tubes in opposition to the potential drop impressed between said electrodes as a result of undesirable feed back action, and having a value such as to effect substantially complete neutralization of said last mentioned potential drop.

15. A high frequency amplifier comprising a vacuum tube having circuits at the input and output sides thereof including radio frequency portions, ohmic resistance in circuit with certain of said radio frequency portions at the output side of said tube, and

traversed by the radio frequency current to develop a radio frequency potential difference across the same, means between said resistance and the input electrodes of said tube for impressing said radio frequency potential difference between said electrodes in opposition to the corresponding radio frequency potential difference impressed between the same as a result of undesirable feed-back action, and means in circuit with said resistance for controlling the same in accordance with the frequency to automatically vary the effect thereof as the feedback varies.

16. A high frequency amplifier comprising a vacuum tube having circuits at the input and output sides thereof including radio frequency portions, a source of space current in said output circuit, ohmic resistance and a condenser in series in circuit with certain of said radio frequency portions at the output side of said tube, and traversed by the radio frequency current to develop a corresponding radio frequency potential difference across the same; said condenser serving to exclude said space current from said resistance and to control the same in accordance with the frequency, and circuit connections between said resistance and the input electrodes of said tube for impressing said radio frequency potential difference between said electrodes in opposition to the corresponding radio frequency potential difference impressed between the same as a result of undesirable feed-back action.

In testimony whereof I affix my signature. 100
BOYD PHELPS.
